United States Patent Office

Des. 185,559
Patented June 23, 1959

185,559

JEWELRY HOLDER

Russel A. McElwee, Manhasset, N.Y.

Application September 19, 1958, Serial No. 52,694

Term of patent 3½ years

(Cl. D33—3)

Fig. 2.

Fig. 1.

Fig. 1 is a side elevational view of a jewelry holder, showing my new design;

Fig. 2 is a front elevational view;

Fig. 3 is a top plan view;

Fig. 4 is a bottom plan view of the same; and

Fig. 5 is a vertical sectional view taken on the line 5—5 of Fig. 3.

I claim:

The ornamental design for a jewelry holder, substantially as shown.
